WINDOW DISPLAY BACKGROUND

Francis Murray, Ponca City, Okla.

Application October 22, 1936, Serial No. 107,099

4 Claims. (Cl. 40—126)

The invention relates to a window display device and more especially to a window changeable display background.

The primary object of the invention is the provision of a background of this character, wherein the same embraces a scene and images and through the instrumentality of light the scene will automatically change for giving attraction when such scene is within a window for the display of merchandise, the said scene during the day time will have display devoid of color and by night through lighting will be possessed of color imitative of a horizon, growing grass and a roadway although the effect may be varied to be imitative of other scenic settings thus rendering the background attractive and artistic in kind.

Another object of the invention is the provision of a background of this character, wherein through the use of motive power motion can be given to the images to render the same animated, for example, persons working within a garden, and in this manner attracting attention of persons where the background is within a display window, the background being of novel construction and the effect thereof is susceptible of changing by day and night.

A further object of the invention is the provision of a background of this character, which is simple in its construction, thoroughly reliable and effective in its operation, susceptible of attracting attention, possessing animation, aesthetic, and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a front elevation of a background constructed in accordance with the invention.

Figure 2 is a rear elevation thereof.

Figure 3 is an enlarged sectional view on the line 3—3 of Figure 2 looking in the direction of the arrows.

Figure 4 is a fragmentary sectional view on the line 4—4 of Figure 3 looking in the direction of the arrows.

Figure 5 is a fragmentary sectional view on the line 5—5 of Figure 3 looking in the direction of the arrows.

Figure 6 is a fragmentary plan view of a floral animation embraced in the background.

Figure 7 is a vertical sectional view of a unit including a lighting device and a modified form of the background.

Similar reference characters indicate corresponding parts throughout the several views in the drawings.

Referring to the drawings in detail, A designates generally the background constituting the present invention and in this instance comprises a substantially rectangular shaped frame 10 preferably made from wood, although it may be made from any other suitable material, this being of any desirable size and of any other shape should the occasion require. Fitted in this frame 10 is a sheet of white crepe paper 11 which is relatively taut and is made secure marginally there-of within the said frame to be bordered by the latter. Upon the exposed side of the sheet paper 11 is arranged images 12, 13, 14, 15, and 16, respectively, each being cut from relatively stiff cardboard blackened. These images are pasted or otherwise made fast upon the sheet paper 11 at selected localities within the frame 10, the image 12 being indicative of a male gardener; the image 13 indicative of a female; the image 14 indicative of a cat; the image 15 indicative of growing tulips and the images 16 indicative of birds. The image 13 has a posture holding a watering pot 17 while the image 12 has a posture holding a hoe 18 which latter is separated from the sheet paper 11 and made from relatively stiff cardboard to effect reality. The hoe 18 is supported in the hands of movable arms 19 and 20, respectively, separate from the sheet paper 11 and swingingly supported on pivots 21 suitably fixed to a hanger 22 arranged in rear of the sheet paper 11 and supported by the frame 10.

The hanger has fitted thereon an electric motor 23 which through a gearing 24 drives a rotatable shaft 25 which extends forwardly of the sheet paper 11 and is fitted with a cam 26 operating on an abutment 27 fixed to the arm 20 so that the said arm 20 will be moved and thus the hoe 18 operated giving appearance of the gardener busily engaged in working the garden. The water pot 17 as held by the image 13 is positioned to indicate the watering of the tulips 15 growing within the garden. The garden representation is indicated at 28 and to give growing grass effect thereto the sheet paper 11 on the rear face thereof has a paper covering 29 of green color and by illumination rearwardly of these sheets the gar-

den area 28 will have a green effect imitative of growing grass therein.

The garden is mapped by a border demarcation 30 which is cut from relatively stiff cardboard, although the material may be glass, paper or other material found desirable and the cut formation is irregular and such cardboard is black, the same being pasted on the outer face of the sheet paper 11 and in this manner there is effected a horizon as at 31 to the scene depicted by the background. The covering crepe paper 29 is cut away immediately rearwardly of the images 12, 13, 14, 15, 16 and 17, respectively, in that such are cut into at determined places as at 32 so as to give natural appearance to these images simulating dressed persons, natural flowers, animals and birds whether the background be illuminated or not.

When the background constructed as hereinbefore set forth is on display within a window or other point of display by day the images are silhouettes and by night the background in the scenic characteristics changes to give color effect thereto with the images silhouetted in such scenic appearance.

For illumination of the background one or several electric lamps can be placed at the rear thereof.

In Figure 7 of the drawings there is shown a slight modification, wherein there is provided a lamp house 33 in which is placed an electric lamp 34 to be illuminated and a reflector 35, respectively, while at the open front of this house 33 is a window 36 embracing the background make-up hereinbefore described and in this fashion a display device with changeable scenic characteristics is had.

Of course, it is to be understood that variations in the images is contemplated and also in the scenic characteristics of the background.

In Figure 3 of the drawings there is shown by dotted lines an electric lamp 37 which is located properly with relation to the background for illumination thereof for color effect thereto through illumination.

It is an aim of the present invention to render the silhouettes animated whether singly or collectively and this is contemplated within the scope of the invention.

It is to be understood that changes, variations and modifications may be made in the invention as fall properly within the scope of the appended claims without departing from the spirit of the invention or sacrificing any of its advantages.

The display background has been described and shown for use in store windows. However, the

device is adaptable for pictures for use in a home such as a room or the like therein.

What is claimed is:

1. A display device comprising a support, a colorless sheet carried by said support and forming a background, silhouettes at the exposed side of the sheet and imitative of animate and inanimate images, means rearwardly of the sheet for effecting color at determined areas thereof on illumination of said sheet, means for rendering a determined silhouette animated, and silhouette borders at the exposed side of said sheet, said coloring means being a colored sheet arranged rearwardly of the first-mentioned sheet. 10

2. A display device comprising a support, a colorless sheet carried by said support and forming a background, silhouettes at the exposed side of the sheet and imitative of animate and inanimate images, means rearwardly of the sheet for effecting color at determined areas thereof on illumination of said sheet, means for rendering a determined silhouette animated, silhouette borders at the exposed side of said sheet, said coloring means being a colored sheet arranged rearwardly of the first-mentioned sheet, and means 20 for projecting light in the direction of said first-mentioned sheet.

3. A display device comprising a support, a colorless sheet carried by said support and forming a background, silhouettes at the exposed side 30 of the sheet and imitative of animate and inanimate images, means rearwardly of the sheet for effecting color at determined areas thereof on illumination of said sheet, means for rendering a determined silhouette animated, silhouette 35 borders at the exposed side of said sheet, said coloring means being a colored sheet arranged rearwardly of the first-mentioned sheet, means for projecting light in the direction of said first-mentioned sheet, and a power unit supported for 40 operating the second-named means.

4. A display device comprising a support, a colorless sheet carried by said support and forming a background, silhouettes at the exposed side of the sheet and imitative of animate and inanimate images, means rearwardly of the sheet for effecting color at determined areas thereof on illumination of said sheet, means for rendering a determined silhouette animated, silhouette borders at the exposed side of said sheet, said coloring 45 means being a colored sheet arranged rearwardly of the first-mentioned sheet, means for projecting light in the direction of said first-mentioned sheet, and a power unit supported for operating the second-named means, the said silhouettes being black and non-penetrating to light. 50
